UNITED STATES PATENT OFFICE.

HENRY M. REICHENBACH, OF ROCHESTER, NEW YORK.

FUEL-SUPPLY DEVICE FOR INTERNAL-COMBUSTION ENGINES.

1,223,109.

Specification of Letters Patent. Patented Apr. 17, 1917.

Application filed January 27, 1915, Serial No. 4,722. Renewed July 10, 1916. Serial No. 108,448.

To all whom it may concern:

Be it known that I, HENRY M. REICHENBACH, a citizen of the United States, residing at Rochester, in the county of Monroe and State of New York, have invented certain new and useful Improvements in Fuel-Supply Devices for Internal-Combustion Engines; and I do hereby declare the following to be a full, clear, and exact description 10 of the invention, such as will enable others skilled in the art to which it appertains to make and use the same.

My invention relates to fuel distributors and carbureters for internal combustion engines or motors.

My invention relates to the provision of a fuel control means responding directly to engine suction through a main controlling or deflector plate arranged in the intake conduit through which passes what is ordinarily called the initial air supply in contradistinction to supply entering through some auxiliary opening.

My device also provides a comparatively simple and cheap instrument for permitting an enlargement of the fuel supply openings upon increase in the demands of the motor, in contradistinction to what is known as a fixed adjustment carbureter or one in which the fuel-emitting orifice remains constant in size throughout the range of engine speeds. The enlargement of the fuel orifice, referred to above, is in direct (as distinguished from differential) proportion to the air passing through the intake conduit.

In the accompanying drawings forming a part of this application, and in which reference symbols indicate corresponding parts in all the views:

40 Figure 1 is a top plan view.

Fig. 2 is a side view partly in section.

Fig. 3 is a horizontal sectional view taken on the line $x-x$ of Fig. 2.

Fig. 4 is a bottom plan view; and

45 Fig. 5 is a sectional view taken on the line $y-y$ of Fig. 1, looking toward the left.

In the drawings, 1 is the fuel supply tank, from which fuel passes through the channel 2 to the fuel distributors 3, which may be of 50 capillary size, arranged in the intake conduit 4. This conduit may be polygonal and is preferably rectangular in cross section, at least behind the point of fuel discharge. These distributors are provided with slots 55 or discharge opening 5, extending in an up

and down direction transversely to the intake conduit, with their edges exposed directly to the draft. Sliding in the upper part of each of the distributors 3, four of which are shown, is a plug or cylinder 6, (though a cap might be used) which serves to close the upper part of the distributor, and thus to close the openings or slots, in its corresponding distributor, in whole or in part, according to its vertical position. 60 These plugs 6 are all shown of equal length and are mounted in a carrying or head piece 7, the vertical position of which, of course, determines the vertical position of the plugs, and consequently the extent to which the 65 slots are open. Into this head 7 is screwed a screw 8, the lower end of which may, as shown in Fig. 5, act as a stop to limit the downward movement of the head, and the upper end of which projects above the 70 head sufficiently far to be engaged by the forked end 8a of a plate 9 hinged at 10 to the top of the intake conduit. I mount upon the top of said conduit 11, a screw with milled nut 12, and said screw passes through 80 an opening in plate 9. Between the milled nut and the plate 9, and around the screw, I place the compression spring 13, which tends to press down the hinged plate, and consequently the head 7, until the lower end 85 of screw 8 rests upon the top of the intake conduit.

Pivoted to brackets on the head 7 is a forked lever 14, fulcrumed at 15 upon a standard or support 16 attached to the top 90 of the intake conduit. At 17 in the other or power end of the lever, is a series of holes, in any one of which is a pin, upon which pin is pivoted a link 18 passing through a slot in the top of the conduit, the lower end of 95 which supports, by the pin shown at 19, the deflector plate 20. The upper end of the link is provided with a screw 21 which is mounted to bear upon the pivot pin at 17. By unscrewing said pin slightly, a certain 100 extent of play between the link and the lever may be effected, so that response of the lever and consequently of the head 7, to the deflector plate movement, need not be immediate. In the outer end of the lever, I 105 provide an adjustable stop 22.

The deflector plate is pivotally hinged in the intake preferably on the bottom thereof, the intake conduit here being of rectangular shape, and extends diagonally upward as 110

shown. At its upper end it may be provided if desired with a vertical portion 22, terminating in a piece 23 adapted to contact with the inside top of the conduit. The 5 upper portion 22 may be skeletonized or may be provided with openings, as shown in Fig. 2, so that there may always be an opportunity for some quantity of air to pass through said plate no matter what adjustment of the parts described is made, and no matter how light the pull of the engine. The nut 12 may be screwed down so far, for instance, that the spring 13 will, through lever 14 and link 18, prevent the deflector 10 plate 20 from yielding to any engine suction at the same time some small quantity of air may pass the fuel discharge openings. These openings may then be almost closed, owing to the position of the closing plugs 20 determined by the position of screw 8. If, however, the spring 13 be properly adjusted the deflector plate will be deflected under engine suction, and the openings of the fuel distributors will respond directly to such 25 deflection and hence respond directly to engine suction.

In some proper place, preferably the bottom of the conduit under the intake deflector plate, an auxiliary valve 23', hinged 30 at 24, and controlled by a spring 25, adjustable at 26 by milled nut 27. This valve may be adjusted to yield under predetermined engine suction, and through it may 35 pass diluting air in quantity additional to that passing by the deflector plate, in proportion to fuel and engine need. In the form shown, the entrance part of my intake conduit is rectangular in cross section, and for this part the rectangular shape is preferred. Farther on I may change the shape 40 in cross section to some other, in this instance a circular shape. In this part I have arranged in the present embodiment of my device, a throttle valve 28, to the shaft of 45 which is attached operating lever 29. I may also provide another arm or lever 30 on the shaft, and in this I have mounted an adjusting screw 31 which is adapted, when the throttle is thrown closed 50 to contact with the flange 32, on the intake conduit by means of which flange my fuel distributor may be bolted or otherwise secured to an engine. This arrangement prevents entire closure of the throttle so that 55 the motor may be kept running idle, on a low speed.

The sign 33 indicates a fuel filter. It will be seen that I have provided in the structure shown and described above, a simple 60 and efficient means of controlling the area of the fuel discharge openings in direct response to the suction of the engine, and have also provided means whereby the parts may be accurately adjusted to the needs of any 65 particular engine and to the wear of such

engine, the area of the openings being always maintained in direct response to engine suction.

Having thus described my invention, what I desire to secure by Letters Patent of the 70 United States, is:

1. In a fuel supply device for internal combustion engines, in combination, a fuel tank, upwardly directed pipes having fuel discharge openings connected with said tank, 75 said openings discharging into the intake conduit, devices for controlling the areas of said openings, a deflecting plate in the intake conduit in front of said fuel openings, arranged to deflect incoming air toward said 80 fuel openings in response to engine suction, and connections between said deflecting plate and said fuel discharge openings, whereby the area of said openings may be made to vary in direct proportion to the deflections of said plate.

2. A means for supplying fuel for an internal combustion engine, in direct proportion to engine suction, which consists of an intake conduit, a deflector plate hinged to 90 the bottom thereof and extending obliquely forward, devices having fuel discharge openings, arranged in said conduit, in front of said deflector plate, means for changing the areas in one direction of said openings, and 95 means connecting said devices with said deflector plate.

3. A means for supplying fuel for an internal combustion engine, in direct proportion to engine suction, which consists of an 100 intake conduit rectangular in cross section, a deflector plate hinged to the bottom of said conduit and of a width corresponding to the width of the conduit and extending obliquely forward, devices having fuel discharge openings, arranged in said conduit, in front of said deflector plate, means for changing the areas of said openings, and means connecting said devices with said deflector plate.

4. A means for supplying fuel for an internal combustion engine, in direct proportion to engine suction, which consists of an intake conduit, a deflector plate hinged to 115 the bottom thereof and extending obliquely forward, devices having fuel discharge openings, arranged in said conduit, in front of said deflector plate, means for changing the areas of said openings, and means connecting said devices with said deflector plate, 120 said conduit being provided with an auxiliary valve at its bottom for admitting diluting air.

5. A means for supplying fuel for an internal combustion engine, which consists of 125 a fuel tank, fuel distributors connected therewith, said distributors being provided with slots, an intake conduit, said distributors being arranged in said conduit, plugs arranged one in each of said distributors and 130

- adapted to be moved up and down therein to vary the area of opening of said slots, a head, a deflector plate in said conduit, and means connecting said head and said deflector plate whereby when the deflector plate is moved in response to engine suction, the head and the connected plugs are moved to vary the area of the openings in the distributors in direct proportion to the movement of the deflector plate.
6. A means for supplying fuel for an internal combustion engine, consisting of a conduit, fuel discharge openings discharging into said conduit, a deflector plate hinged to the bottom of said conduit, and spring supported in an oblique forward direction with its upper end near the said discharge openings, the upper end of said deflector plate having been bent upward in a vertical direction.
10. 7. In a means for supplying fuel for an internal combustion engine, in direct proportion to engine suction, which consists of an intake conduit, fuel discharge openings in said conduit, a deflector plate arranged to deflect air past said openings, means for controlling the area of said openings, a head on which said means are mounted, a lever to which said head is connected, a spring for holding said head depressed, a pivot for said lever, and a link connected to said lever the other side of said pivot, said link supporting the deflector plate, the arrangement being such that in response to engine suction the deflector plate is depressed to admit more air, and the areas of the discharge openings enlarged in direct proportion to such depression so that the supply of fuel is increased as the supply of air is increased.
15. 8. A means for supplying fuel for an internal combustion engine, in direct proportion to engine suction, which consists in combination, of an intake conduit, a deflector plate hinged to the bottom thereof, fuel distributors discharging into said conduit near the upper end of said deflector plate, means for controlling the fuel discharge area, a head to which said means are connected, a pivoted plate having its free end resting upon said head, a screw passing through said plate, a milled nut for said screw, a spring between said nut and said plate whereby more or less pressure may be exerted upon said plate and hence upon the head, and a lever connection between said head and said deflector plate, whereby the head moves to permit the area of the openings to be enlarged in direct response to movement of the deflector plate, in opposition to said spring, and whereby the spring may be adjusted to cause said deflector plate to respond to engine suction at any desired pressure.
20. 9. In combination, a conduit for an internal combustion engine, a deflecting plate pivoted on the bottom of said conduit to extend obliquely forward, openings in the forward part of said plate, pipes of capillary dimensions, openings in said pipes in front of said plate openings, means for varying the dimensions of said pipe openings, and connections between said dimension varying means and said plate, whereby deflection of the plate will vary the dimensions of the pipe openings.
25. 10. In combination, a conduit having several sides, for an internal combustion engine, a deflecting plate pivoted to one of said sides, and arranged to extend obliquely forward, an opening in the forward part of said plate, fuel supply means, an opening in said fuel supply means in front of said plate opening, means for varying the area of discharge of said fuel supply opening, and a connecting means between said area varying means and said plate, whereby movement of the plate will vary the area of said fuel supply means.
30. 11. In a fuel supply device for internal combustion engines, in combination, an intake conduit having several sides, an air deflecting plate mounted on one of said sides, and extending forward to close the conduit, the forward end being free to yield under the pressure of incoming air, a device having an opening for fuel discharge, arranged in front of said deflecting plate, a device for changing in one dimension, the area of said discharge opening, and means connecting said area changing device and said deflecting plate, whereby as said plate yields to incoming air, the area of said opening increases.
35. 12. A means for supplying fuel to an internal combustion engine, in direct proportion to engine suction, which means consists of an intake conduit, a deflector plate yieldingly mounted at one end upon said conduit, and extending obliquely forward, a fuel supplying means discharging into said conduit and provided with a discharge opening opposite the forward end of said plate, a device for changing the discharge area of said opening, and means connecting said device with said deflector plate, whereby deflection of said plate may increase the area of said opening.
40. 13. A means for supplying fuel to an internal combustion engine, consisting of a conduit polygonal in cross section, fuel supplying means having an opening into said conduit, and a deflector plate hinged to one of the walls of said conduit, said plate being yieldingly supported to extend obliquely forward toward said fuel opening with its forward end near the fuel discharge opening, and having its forward end bent.
45. 14. In a fuel supply device for internal combustion engines, in combination, a fuel

5 tank, a pipe having a fuel discharge opening arranged to discharge into said conduit, a device for controlling the area of said opening, a deflector plate in said conduit in front of said opening, arranged to yield to air pressure, to deflect air toward and past said opening in response to engine suction, a device to vary the area of fuel discharge, and means connecting said device and said

plate, whereby as the plate yields to incoming air, the area of said opening becomes greater. 10

In testimony whereof, I affix my signature, in presence of two witnesses.
